UNITED STATES PATENT OFFICE.

AZEL CLARENCE HOUGH, OF JANEVILLE, WISCONSIN, ASSIGNOR TO HOUGH SHADE CORPORATION, OF JANEVILLE, WISCONSIN, A CORPORATION OF CONNECTICUT.

VENTILATING-SCREEN.

1,247,599.

Specification of Letters Patent.

Patented Nov. 20, 1917.

Original application filed February 10, 1917, Serial No. 147,790. Divided and this application filed June 8, 1917. Serial No. 173,631.

To all whom it may concern:

Be it known that I, AZEL CLARENCE HOUGH, a citizen of the United States, and resident of Janesville, county of Rock, State 5 of Wisconsin, have invented an Improvement in Ventilating-Screens, of which the following description, in connection with the accompanying drawings, is a specification, like letters on the drawings representing 10 like parts.

The present application relates to a modified form of my ventilating screen invention, as described and claimed broadly in my Patent No. 1,218,556, issued March 6, 15, 1917. The present application is a divisional of my pending application Serial No. 147,790, filed February 10, 1917, in which pending application I have elected to claim one form of my ventilating screen 20 construction. In the present divisional application I have elected to describe, illustrate and claim the form of my ventilating screen construction which includes a combined spacing and warp binding element 25 between the slats constituting the ventilating portion of my screen. While I prefer to construct a woven screen having a non-ventilating portion in combination with a ventilating portion or portions therewith, it 30 will be readily understood that I may construct a screen embodying the present invention comprising exclusively a ventilating construction. One of the important advantages of the screen utilizing a combined 35 spacing and warp binding element consists in the ease and facility with which such a screen may be built; in the firm, secure and permanent manner in which each slat is held, irrespective of the spacing therefrom 40 to adjacent slats; and in the further important feature of enabling a variation in spacing to be made wherever desired.

Further features of the invention, details of construction, and novel combinations of 45 parts will be hereinafter more fully pointed out and claimed.

Referring to the drawing illustrating a preferred embodiment of the invention,

Figure 1 is a fragmentary view of a venti- 50 tilating screen embodying the invention;

Fig. 2 is a cross sectional view on the line 2 of Fig. 1.

Fig. 3 is an enlarged detail between adjacent slats, and the combined spacing and 55 warp binding device, shown in cross section.

Fig. 4 is a cross sectional view of a modification.

As shown in the drawing, Fig. 1 comprises a portion of a ventilating screen having a non-ventilating portion, consisting in 60 the relatively broad slats 1, 2, 3 and 4, closely woven by pairs of warp cords or strands, 5, 6, 5, 6, which may be of any number and constituting any desired proportional part of the screen, together with 65 a ventilating section. This ventilating portion comprises a plurality of slats, preferably narrower than the slats constituting the non-ventilating portion, which slats may be variously spaced and are here shown, for 70 the sake of example, as a set of slats 7, 8, 9 and 10, being spaced substantially equidistant from each other and slats 11 and 12 showing a greater spacing.

It will be understood that in a woven 75 screen it is necessary to have the warp cords or strands tightly interlaced about the slats in order to prevent the slats from becoming loose and working endwise. This has been one of the difficulties to be overcome 80 and I accomplish this purpose in my present form of ventilating screen by providing combined slat-spacing and warp cord binding elements as indicated at 13, 13. These elements may be of any desired length, such 85 for example as those illustrated at 14, giving greater spacing, and they hold the slats spaced in their predetermined position while tightly binding or clamping the warp cords thereabout. These spacing and clamping 90 elements may be, also, of any desirable material, and may be either small tubular members, or split tubular members, the latter being clamped about the warp strands firmly binding them in position during the 95 manufacture of the screen. Fig. 3 clearly illustrates the binding and spacing feature of such elements. I find that tubular strips of celluloid, cut into suitable lengths and split, are capable of advantageous use for 100 these elements. Also similar metallic elements may be utilized, and clamped into position as each successive slat is incorporated in the screen. In using celluloid or the like plastic material, the element can 105 be applied while in a plastic state, and thus more firmly and solidly unite and hold the warp strands and space the slats from each other, a suitable tool serving to apply and force the material while plastic into shape. 110

I have shown at 20 and 21 the usual reinforcing strips about the topmost slat 22, and it will be understood that such reinforcing strips may be applied at different 5 places throughout the length of the screen, where desired. It will also be appreciated that the ventilating section in a woven screen of this type may be applied at the top, at the bottom, or at any point intermediate 10 the extent of the screen, and that a plurality of such ventilating sections may be formed if desired. Also I may provide a section of narrow spaced ventilating slats at the upper part of the screen and a section 15 of wider spaced slats at the lower part, or in reverse order, the combined spacing and warp clamping elements firmly, securely and permanently binding the spaced slats in their position.

20 In the modification illustrated in Fig. 4, I have shown a further advantage incident to my type of combined spacing and clamping device. This consists in making a ventilated screen, or a ventilated portion in a screen, 25 without interlacing the warp cords about the slats, but by relying upon the clamping devices to secure the same. Referring to Fig. 4, the slats 30 and 31 are secured by the warp cords 32 and 33 running alongside 30 said slats parallel with each other and on the same side, being engaged, clasped and clamped by the sleeves 35, 35, about the cords, as shown. It will be understood that in view of this modification I do not intend 35 that the term "woven screen" should be limited to a weaving of the warp strands interlaced about the slats, but may apply equally to the construction illustrated in Fig. 4. This arrangement of having the warp cords 40 running parallel or on the same side of the slats, may be utilized only for the ventilating section, if desired, and then interlaced forwardly and backwardly or to and fro about the remaining slats in the non-ventilating 45 section.

My invention is further described and defined in the form of claims as follows:

1. A woven screen of the kind described, comprising a plurality of transverse slats held together by woven warp strands interlaced over the front and back of alternate slats, in combination with a combined spacing and strand holding element engaging the warp strands between adjacent slats. 50 55 60 65 70 75 80 85 90 95 100 105 110 115 120

2. A woven screen of the kind described, comprising a ventilating portion and a non-ventilating portion, said ventilating portion consisting in a plurality of transverse slats held together by woven warp strands interlaced over the front and back of alternate slats, in combination with a combined spacing and strand holding element between each 80 85 90 95 100 105 110 115 120

3. A woven screen of the kind described, comprising a plurality of ventilating portions and a non-ventilating portion, each ventilating portion consisting in a plurality of transverse slats held together by woven warp strands interlaced over the front and back of alternate slats, in combination with a combined spacing and strand holding element between each slat. 65 70 75 80 85 90 95 100 105 110 115 120

4. A woven screen of the kind described, comprising a plurality of transverse slats spaced from each other at varying distances, and being held tightly together by woven warp strands interlaced over the front and back of alternate slats, in combination with combined spacing and strand clamping sleeves, the length of said sleeves determining the spacing of adjacent slats. 75 80 85 90 95 100 105 110 115 120

5. A woven screen of the kind described, comprising a ventilating portion and a non-ventilating portion, said non-ventilating portion consisting in slats held closely together by woven warp strands interlaced thereabout, said ventilating portion having the slats woven farther apart than the non-ventilating section, and so woven by said warp strands as to permit the said "ventilating section" slats to be spaced from each other and from the end slat of the non-ventilating portion, in combination with means engaging the warp strands between each of the slats in said ventilating portion to hold said warp strands tightly in engagement with, and spaced from, adjacent slats. 85 90 95 100 105 110 115 120

6. In a woven screen, a non-ventilating, closely woven portion, comprising a plurality of transverse slats held together by woven warp strands, and a ventilating portion, comprising a plurality of transverse slats held together with the warps running parallel, and combined warp engaging and slat spacing devices, clasping said warp strands between the spaced slats. 100 105 110 115 120

7. In a woven screen, a non-ventilating, closely woven portion, comprising a plurality of transverse slats held together by woven warp strands, interlaced over the front and back of alternate slats, in combination with a ventilating portion comprising a plurality of transverse slats with the woven warp strands non-interlaced, a combined spacing and strand holding element between each of said spaced slats encompassing and locking said warp cords tightly about adjacent spaced slats. 110 115 120

In testimony whereof, I have signed my name to this specification, in the presence of two subscribing witnesses.

AZEL CLARENCE HOUGH.
